UNITED STATES PATENT OFFICE.

DUDLEY EUGENE LATHAM, OF NEW YORK, N. Y.

GARMENT-SUPPORTER.

1,238,306.

Specification of Letters Patent. Patented Aug. 28, 1917.

Application filed April 5, 1912, Serial No. 688,666. Renewed October 1, 1915. Serial No. 53,658.

To all whom it may concern:

Be it known that I, DUDLEY EUGENE LATHAM, a citizen of the United States, residing at New York city, in the county of New York and State of New York, have invented new and useful Improvements in Garment-Supporters, of which the following is a specification.

My invention relates to hose supporters and has particular application to the retaining of men's socks in correct position on the person with a large degree of comfort when worn. Furthermore, my improved garter is of a construction possessing features of decided convenience in the initial attachment of the garter on the leg and which is attended by added security to the support of the garment.

The features of my invention are preferably incorporated in the double fastener type of garter wherein the sock is supported on each side. The more important of these are the supporting of the attaching pieces from a single point of attachment to a band which desirably is adjustable on the leg, the pivotal attachment of the supporting pieces that they may adjust themselves to correct position and the provision for convenient attachment of the garter to the leg. As a result of my arrangement a band, properly adjusted in fixed relation to the leg is provided, from which the supporting pieces depend in a manner whereby a down pull thereon will result in a longitudinal pull throughout both the supporting pieces and band which, taken together, form a continuous band encircling the leg.

These and other features and advantages of my improved garter will be readily understood by reference to the accompanying drawing in which the reference numerals of this description are applied to corresponding parts in all the views.

Figure 1 shows in perspective a preferred form of garter positioned on the leg. Fig. 2 shows an enlarged perspective of a similar garter with additional adjustments provided for.

In the figures 1 indicates the usual circular band preferably of elastic material to surround the leg of the wearer and having its ends secured by any suitable engaging means, that as shown being the customary glove fastener consisting of the compressible ball member 2, secured on one of the

band ends, to be engaged by the socket member 3, secured on the other band end, these engaging parts affording a pivotal connection having an additional important function as hereinafter described.

From the band 1 the attachment or supporting pieces 4 and 5 depend to be secured to the garment by suitable fasteners 6—6 carried on their ends. The fasteners shown are of an approved form, but which I desirably alter for the purpose of improving its grip on the garment by corrugating their opposed gripping surfaces 7.

In the embodiment of my invention referred to, the supporting pieces with the fasteners are attached each to an end of the band by means of connecting pads 8—8 attached to the band ends and to the supporting pieces. To these pads 8, as shown, the engaging ball 2 and socket 3 are directly attached. In this arrangement upon disengagement of the engaging members the band ends, likewise the supporting pieces, are separated and the parted band falling loosely to the rear permits removal of the garment. Obviously the garter may conveniently be readjusted in position on the leg by bringing the connecting pads into forward engaging position and connecting the engaging ball and socket members. To facilitate connecting the band the outer pad may have a finger-tab 9.

The initial attachment and adjustment of the garter may readily be accomplished by the attachment of one of the fasteners 6 to the garment, clasping the band in position encircling the leg and finally attaching the other fastener higher or lower on the garment to secure the tension desired, when, by reason of the pivotal character of the engaging members 2 and 3 a self adjustment of the garter to proper position on the leg will result.

The described garter may be constructed in various ways and of any desired material. As illustrated the band 1 may be of elastic cloth having its one end attached as by sewing between the layers of a two piece leather pad 8 and its other end looped into a slotted piece 10 (secured to the other similar pad) and having its end attached to a sliding part 12 thereby providing for an adjustment of the band in a customary manner. The supporting pieces 4 and 5 may be provided with sliding-pieces 14 to provide for similar ad-

justments, as shown in Fig. 2, whereby the fasteners may be raised or lowered with respect to the band.

Having described my invention, what I claim is:

1. As a new article of manufacture, a band garter for men's wear comprising an adjustable band to encircle the leg, separable means to secure the band ends together, independent supporting pieces secured to the respective band ends to depend from a common point on the band, fasteners on the supporting pieces to engage the garment and said band being adjustable without affecting the supporting pieces, substantially as described.

- 15

2. As a new article of manufacture, a band garter for men's wear comprising an adjustable band to encircle the leg, separable pivotal means to secure the band ends together, independent adjustable supporting pieces secured to the respective band ends and fasteners on the supporting pieces to engage the garment.

In testimony whereof I have signed my name to this specification in the presence of two subscribing witnesses.

DUDLEY EUGENE LATHAM.
